UNITED STATES PATENT OFFICE.

WILLIAM H. COLE, OF CHARLES CITY, IOWA.

COMBINED DOOR-HANGER AND TRACK FOR EDGEWISE-MOVABLE DOORS.

1,004,746.

Specification of Letters Patent.

Patented Oct. 3, 1911.

Application filed March 9, 1911. Serial No. 613,278.

To all whom it may concern:

Be it known that I, WILLIAM H. COLE, a citizen of the United States, residing at Charles City, in the county of Floyd and 5 State of Iowa, have invented certain new and useful Improvements in a Combined Door-Hanger and Track for Edgewise-Movable Doors; and I do declare the following to be a full, clear, and exact description 10 of the invention, such as will enable others skilled in the art to which it appertains to make and use the same.

This invention relates to improvements in a combined door hanger and track for edge- 15 wise movable doors.

One object of the invention is to provide an improved construction and arrangement of roller carriages and an improved construction of track adapted to receive the 20 carriages whereby the door is movably supported and the carriages protected from the weather.

With this and other objects in view the invention consists of certain novel features 25 of construction and arrangement of parts as will be more fully described and particularly pointed out in the appended claims.

In the accompanying drawings: Figure 1 is a front view of part of a barn door showing 30 the application of the invention parts being broken away; Fig. 2 is a vertical cross section of the same on the line 2—2 of Fig. 1; Fig. 3 is a rear view of one of the carriages; Fig. 4 is a detail perspective view 35 of one of the hangers forming part of the carriage.

Referring more particularly to the drawings, 1 denotes the track of my improved support said track being preferably formed 40 from heavy sheet metal bent to form a vertical attaching flange 2, an inclined cover plate 3, a vertical front or outer wall 4, an inwardly projecting horizontal track rail 5 and an upwardly projecting guide flange 45 5^a formed on the inner edge of the track rail. The attaching flange 2 is secured to the side of the barn or other support by screws or other fastening devices. By thus constructing and arranging the track it will 50 be seen that the same forms a protective housing as well as a track rail for the door supporting devices.

Adapted to be engaged with the track rail 4 are door supporting carriages 6 said 55 carriages comprising hangers 7 formed from rods bent into substantially U-shaped frames.

The looped portion of each hanger frame is bent laterally at substantially right angles to form the door engaging portion 8 of the hanger. The free ends of the frame are 60 bent outwardly at right angles to form bearing studs or pintles 9 on which are rotatably mounted supporting rollers 10. The outer ends of the studs 9 are connected and the rollers 10 held in position thereon by plates 65 11 said plates bracing the ends of the hangers and preventing the same from spreading, as well as holding the rollers 10 thereon.

The door 12 is pivotally connected to the hangers by straps 13 adapted to embrace the 70 top edge of the door and which are bent midway between their ends to form bearings 14 adapted to be engaged with the door attaching portions 8 of the hangers. The ends of the straps after forming the bear- 75 ings 14 are bent outwardly and downwardly at right angles and are bolted or otherwise secured to the sides of the door thus loosely connecting the same to the hanger whereby the door is movably suspended from the 80 track and may be readily opened and closed by a slight push or pull in the desired direction.

From the foregoing description, taken in connection with the accompanying drawings, 85 the construction and operation of the invention will be readily understood without requiring a more extended explanation.

Various changes in the form, proportion and the minor details of construction may 90 be resorted to without departing from the principle or sacrificing any of the advantages of this invention as defined in the appended claims.

Having thus described my invention what 95 I claim is:—

1. A door support comprising a track, door supporting carriages comprising hangers constructed of rods bent to form an off-set U-shaped door engaging portion and right angular bearing studs, extending in the same direction and in a plane parallel with said U-shaped member, rollers rotatably mounted on said studs adapted to engage and travel on said track, and means to connect said hangers with a door. 100

2. A door support comprising a track, door supporting carriages, comprising hangers constructed of rods bent to form an off-set U-shaped door engaging portion and right angular bearing studs, rollers rotatably mounted on said studs and adapted to en- 110

gage and travel on said track, and straps bent to form bearings adapted to be pivotally engaged with the door engaging portions of said hangers, said straps having their ends secured to the opposite sides of the door whereby the latter is hingedly secured to the hangers.

In testimony whereof I have hereunto set my hand in presence of two subscribing witnesses.

WILLIAM H. COLE.
